DESCRIPTION

FIG. 1 is a front perspective view of the casement window lock handle of the present invention.

FIG. 2 is a front elevational view of the casement window lock handle shown in FIG. 1.

FIG. 3 is a right side elevational view of the casement window lock handle shown in FIG. 1.

FIG. 4 is a left side elevational view of the casement window lock handle shown in FIG. 1; and,

FIG. 5 is a bottom plan view of the casement window lock handle shown in FIG. 1.

The broken lines are shown for illustrative purposes only and form no part of the claimed design. The surface of the article not shown in the drawing or described in the specification forms no part of the claimed design.
